UNITED STATES PATENT OFFICE.

EDWARD E. CLEMENT, OF WASHINGTON, DISTRICT OF COLUMBIA, ASSIGNOR, BY
MESNE ASSIGNMENTS, TO JAMES R. GARFIELD, TRUSTEE, OF CLEVELAND, OHIO.

TELEPHONE-EXCHANGE SYSTEM.

1,197,185.

Specification of Letters Patent. Patented Sept. 5, 1916.

Application filed June 18, 1912. Serial No. 704,327.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object to provide automatic switching means which will be automatically self-actuating, and will control preselecting means as for example subscribers' or central office senders, within limits determined by such means; or in other words, this system contemplates that the switches shall send back impulses the length of which will be determined by 15 their own time constants, to step or otherwise actuate the sending devices, which by operating to cut off at a fixed or zero position, will determine the number of impulses and thereby the extent of actuation of the 20 switches.

The present application is in the nature of an improvement over my prior applications as follows: Serial No. 611,923, filed March 2, 1911, and Serial No. 644,076, filed 25 August 15, 1911.

The invention is illustrated in the accompanying drawings in which—

Figure 1 is a diagram of a simple embodiment of the invention, and is to be read in conjunction with Fig. 1^c. Fig. 1^a is a similar diagram of a modified form of the invention, and is to be read in conjunction with Figs. 1^b and 1^c. Fig. 1^b is a diagram of a subscriber's line circuit and central office primary and secondary connecting means. Fig. 1^c is a diagram showing selector and connector switches. Figs. 2, 3, 4, 5 and 6 taken together contain a complete diagram of a commercial semi-automatic system embodying the same principle as Fig. 1^a. In this form a key set is employed for controlling the impulses.

Referring to Fig. 1, the substation 653 is shown equipped with a standard common battery telephone set, from which the line wires 601—602 extend to the central office and terminate on contacts of a cut-off relay R⁶⁰ through which they are normally connected to a line relay R⁵¹ and battery on one side and ground on the other. The arrange-

ment shown is the so-called two wire multiple, with extensions 603 and 604 to the jack 600, with which coöperates a plug 654 having its tip and sleeve conductors connected to the cord conductors 696 and 697, terminating at the condensers 652. Tip and sleeve relays R⁶² and R⁶³ are provided as is usual with this type of cord and jack. The relay R⁶² controls the circuit of the supervisory lamp 605 and the release circuits 606—607 for the automatic switches in Fig. 1^c, these circuits being connected to the trunk conductors 608—609 extending to the first selector switch S¹¹, which has the usual vertical and rotary relays R⁶⁴ and R⁶⁵, private magnet M²⁵, test relay R⁶⁶, release magnet M²⁶, talking wipers w⁶⁰⁸—w⁶⁰⁹, test wiper w⁶¹⁴, side switch arms 610, 611, 612, and 613, vertical magnet M²⁷ and rotary magnet M²⁸. The second selector switch S¹² has relays, magnets, and contacts corresponding to those of the first selector with the exception that the vertical and rotary relays of the second selector when simultaneously energized close their own release circuit and also a branch through the test bank and test wiper of a first selector temporarily connected therewith, to the release relay of said first selector. The connector switch S¹³ has vertical and rotary magnets and relays, and a test or private normal magnet, similar in other functions to those of the selectors. The vertical and rotary relays control their own release circuit and also the back release the same as in the second selector, but the functions of the magnet M⁵⁶ include the test of the line wanted, and the release of the switch if that line is busy. The trunk wires 615—616 of the connector terminate at the condensers 619 and on the switch side of the condensers the conductors 617 and 618 are extended through contacts of the ringing relay R⁷⁶ to the side switch arms 620 and 621, by which they are connected during conversation to the talking wipers w⁶²⁵—w⁶²⁶, and thereby connected to the contacts of the wanted line. Further detailed description of the line and cord circuit in Fig. 1 and the general switch circuits in Fig. 1^c will not be given, as none of the features so far mentioned form any part of the present invention, except in so far as they contribute to completeness. The circuits illustrated in Fig. 1^c are those of the ordinary well

known Strowger system, employing selector switches of the type shown in Letters Patent granted to Keith and Erickson March 13, 1906, Nos. 815,176 and 815,321. In order 5 to enable the connector circuit of Fig. 1^c to be employed with a two wire multiple line circuit as shown in Fig. 1, the Strowger circuit is modified by the introduction of condensers 619, the tip and sleeve relays 10 R⁷² and R⁷³, and the ringing relay R⁷⁶ with its interrupter I⁵ and lockout relay R⁷⁴. These parts are substantially as shown and described in my prior application Serial 15 No. 428,865, filed April 23, 1908, and also form no essential part of the present invention.

For the purposes of the present invention, and in order to enable each of the 20 switches S¹¹, S¹² and S¹³ to generate its own actuating impulses, I provide the vertical 25 magnets M²⁷ and M³⁰ with interrupter contacts x controlled by the magnet armature, these contacts in each case being normally closed and included in the circuit of the vertical 30 relay R⁶⁴ or R⁶⁷. In the case of the connector, the vertical and rotary magnets M³⁴ and M³⁵ are each provided with interrupter contacts x, both pairs of which are normally closed and included in series in 35 the circuit of the vertical relay R⁷⁰. The result of this arrangement is that without other change in any switch, when any one of the actuating magnets is properly connected by means of the side switch, it will 40 make and break the circuit of its associated controlling relay, which in turn will make and break the magnet circuit, thus producing a reciprocal action which insures not only complete operation of the working 45 magnet for each step, but also sends back sharp clear line impulses to affect the relays of the sender.

Turning to Fig. 1, the operator's sending device is generally designated by the 50 numeral 627. It consists of four rotary disks 628, 629, 630 and 631, each of which is fitted with means for turning it through different determinate angles by hand. In the diagram the means indicated are arms 55 with finger holds which serve also as pointers to sweep over numbered arcs. Connected to each disk is a ratchet or star wheel 632, 633, 634 or 635. These are controlled by anchor escapements carried on the armature 60 levers of electromagnets 636, 637, 638 and 639. Associated with the disks are relays 640, 641, 642 and 643, controlling the actuating magnets and responding to the line 65 impulses in succession. Each disk has a retractile spring, and each scape wheel has a portion of its surface smooth, to permit the spring to move the disk back some distance after the working impulses cease. During this extra movement of each disk 65 it carries a tooth 644, 645, etc., past contacts

to send a rotary impulse, and into engagement with other contacts which shift the control circuit to the next disk. R⁷⁷ is the starting relay, which connects the vertical and rotary wires 648 and 649 to the trunk 70 wires 608 and 609, in response to the actuation of the starting key 650. In addition to the contacts of this relay I have shown a key 651 individual to each trunk, so that the sender 627 may be used with a considerable number of trunks 608-609. This mode of connection however is intended merely for descriptive purposes and not as a limitation. It may be varied in any of the ways described in my prior applications 75 Serial No. 323,096, filed June 23, 1906; Serial No. 327,096, filed July 20, 1906; Serial No. 345,167, filed November 26, 1906; Serial No. 408,039, filed December 26, 1907; Serial No. 428,865, filed April 23, 1908; and 80 others. It should also be understood that the plug and cord connection between the trunk wires 608-609 and the line wires 601-602 may be replaced by any desired primary selecting means, such as shown in 85 any of the applications herein named; or the line may be connected direct to the trunk conductors, with condensers 652 interposed if desired. The sender 100 may also be located at a subscriber's station as well as at 90 a central office, the necessary changes to effect this or other modifications referred to being well within the scope of any telephone engineer or circuit man.

In Fig. 1^a the sender 627 of Fig. 1 is substituted by a set of key strips K¹⁰, K¹¹, K¹² and K¹³ similar to those shown by my application herein referred to. Associated with each strip of keys is a step by step switch, 414, 415, etc., operated over the 105 same circuits as the disks 628, 629, etc., of Fig. 1. The called subscriber's number is set up on the key strips in the usual manner and the connective operation of the switches started by the closure of the starting key 110 SK', in the actuation of the starting relay R⁸². Magnets M³⁸, M³⁹, etc., are the stepping magnets for the switches 414, 415, etc., respectively, and magnets M⁴², M⁴³, etc., are the corresponding release magnets. Relays 115 R⁸³, R⁸⁴, etc., are the repeating relays which are actuated in synchronism with the repeating relays of the several switches and correspond to relays 640, 641, etc., of Fig. 1. Relays R⁸⁷, R⁸⁸, etc., and R⁹¹, R⁹², etc., are 120 circuit shifting relays which subserve similar functions to those of the springs 662, 663, 664, etc., of Fig. 1.

Fig. 1^b is a diagram of a subscriber's terminal apparatus and operator's listening 125 equipment, similar to that shown in Fig. 1, and to be used in conjunction with Fig. 1^a.

The operation of the apparatus and circuits in Figs. 1 and 1^c is as follows: The subscriber 653 calls by closing his line cir- 130

cuit, relay R^{61} lights its lamp, plug 654 is inserted in jack 600, relays R^{63} — R^{60} are energized in series, relay R^{62} is energized, and the operator ascertains the number wanted in the usual or any desired way. If key 651 is employed, it is actuated to cut off the trunk from the cord, and connect conductors 608—609 to the contacts of the starting relay R^{77} . The number wanted is then set up by turning the disks 628, 629, 630 and 631 until their respective arms or pointers rest over numerals corresponding to the several digits of the number. The turning of these disks completes the circuits of their respective relays 640, 641, etc., and turns the ratchets 632, 633, etc., through angular distances corresponding to the several digits. The starting key 650 being depressed, circuit of relay R^{77} is closed as follows: B, 655, 656, 650, 657, R^{77} , ground, B. The energization of relay R^{77} connects 649 to 658 and 648 to 659, and the relay locks itself on wire 660. Circuit is then completed from the battery to the switch S^{11} in Fig. 1^c as follows: B, 655, 640, 661, 662, 663, (628 being off normal) 649, 658, 608, (into Fig. 1^c) 611, contact x of relay M^{27} , R^{64} , ground, B. Magnet R^{64} is energized, closing circuit of M^{27} , which is energized and breaks the contacts x apart at the end of its stroke, but steps the switch spindle and wipers up one step before breaking. The separation of contacts x opens the circuit of relay R^{64} , which becomes de-energized and in turn opens the circuit of magnet M^{27} , which becomes de-energized and closes contacts x thereby closing the former circuit of relay R^{64} , which again becomes energized, again energizes magnet M^{27} , and so on, the stepping up of the switch S^{11} and the making and breaking of the circuit at x being repeated so long as the springs 662—663 in Fig. 1 remain closed. These springs are opened when the arm of disk 628 has been returned to zero, which requires as many current impulses as the forward steps through which it was moved in setting. As each current impulse is produced in the actuation of the switch S^{11} one step, it is obvious that the switch has been set forward or upward a number of steps corresponding to the digit previously determined.

The disk 632 has ratchet or star teeth only part way around its circumference, there being ten teeth on each side and smooth spaces intervening. This is for the purpose of permitting lost motion after the number has been received, so that the spring sets 664—665 and 662—663—666 may be operated in succession. The closure of the first named set produces a rotary impulse for the switch S^{11} through the following path: B, 655, 672, 664, 665, 648, 659, 609, 612, R^{65} , ground, B. R^{65} becomes energized and closes the circuit of M^{25} , which becomes energized

and steps the side switch arms all around one step, shifting the trunk wire 608 onto a dead contact and closing circuit of rotary magnet M^{28} , which rotates the spindle and wipers to find an idle trunk to a second selector, 70 in the ordinary manner. In the meantime the disk 628 being forced past spring 664 by its retractile spring, shifts wire 649 from relay 640 to the path 667, and thereby connects relay 641 to the trunk 608. When 75 an idle trunk has been found, the side switch of selector S^{11} takes its last step, as well understood without explanation, and the trunk wire 608 is at once connected to 693, whence a circuit is established from 629 80 to S^{12} as follows: B, 655, 641, 685, 675, 669, 667, 666, 663, 649, 658, 608, 693, x , R^{67} ground to B. The operation of selector S^{12} then ensues in precisely the same manner as that of selector S^{11} , and when the disk 629 reaches 85 zero position a rotary impulse is sent over the path: B, 655, 690, 673, 674, 670, 648, 659, 609, 694, R^{68} , ground, B. Selector S^{12} then finds an idle trunk to a connector S^{13} , wire 693 in the meantime remaining open at the 90 side switch, and at the end being connected to 615. A path for the third set of impulses is then closed as follows: B, 655, 642, 686, 679, 677, 671, 668, 669, 667, 666, 663, 649, 658, 608, 693, 615, contacts M^{34} and M^{35} 95 in series, R^{70} , ground to B. R^{70} actuates the magnet M^{34} to step the switch up to the desired row, when the disk 630 operates as the preceding disk mechanisms did, to cut off relay 642, send a rotary impulse and shift the 100 circuit 671 to the next path, 687, leading to the relay 643. In the connector the side switch has shifted in response to the rotary impulse at x , so that M^{34} is cut out and M^{35} is cut on to be controlled by R^{70} . Further 105 impulses from x follow this path: B, 655, 643, 687, 684, 695, 678, 677, 671, 668, 669, 667, 666, 663, 649, 658, 608, 693, 615, to relay R^{70} through x — x . Magnet M^{35} then steps the switch around to the wanted line terminals and the next rotary impulse causes the line to be tested, and if clear the side switch takes its last step, 620 and 621 connecting the trunk wires 617 and 618 to the line through wipers w^{625} — w^{626} . Relay R^{73} connects the ringing relay to battery, the interrupter I^5 causes its intermittent energization, the wanted subscriber is rung, and when he answers the relay R^{72} causes the energization of the lockout relay R^{74} , and 120 conversation proceeds. In the meantime, the final step of disks 635 and 631 after sending the rotary impulse over wire 670 opens 687 at 684—647, and also opens the locking circuit 689—660 of relay R^{77} , whereby the 125 sender 627 is entirely cut off from the trunk wires 658—659, 608—609. The operator may then throw up the key 651, or if this key is replaced by an automatic secondary selector of the type set forth in my prior 130

applications referred she will not have to perform any act, but merely wait to receive other calls.

The operation of the switch control as embodied in Figs. 1^a and 1^b is as follows: The operator upon perceiving the call signal plugs in on the calling line, operates the key 651 (Fig. 1^b) and after ascertaining the number of the wanted subscriber, all in a manner as previously described, sets up the number on the key strips K¹⁰, K¹¹, etc., and depresses the starting key SK'. Assuming that the number wanted is 2463, the operator closes the second key k² in the strip K¹⁰, k⁴ in K¹¹, k⁶ in K¹², and k⁸ in K¹³, and upon closure of the starting key SK', the starting relay R⁸² is energized and locks itself to ground through armature r⁸²¹, locking wire 418, and armature r⁹⁴¹. The attraction of armature r⁸²² connects the relay R⁸³ in series with the tip impulse wire 658 so that it will be actuated in synchronism with the tip relay and associated stepping magnet of the first selector (Fig. 1^c) in the same manner as above described. The circuit of relay R⁸³ may be traced as follows: battery, R⁸³, 419, r⁹¹¹, 420, r⁸²², tip impulse conductor 658, contacts of operator's key 651 (Fig. 1^b) and over tip conductor 608 to the circuits in Fig. 1^c as above traced in the previous description of operation. Each actuation of relay R⁸³ completes the energizing circuit of stepping magnet M³⁸ which actuates to step around the spindle of switch 414, and with it the wiper 421 engaging the contacts successively, one at each actuation of the magnet M³⁸. The switch 414 thus steps in synchronism with the controlled selector switch and upon engagement of the wiper 421 with the second contact in its bank, the circuit of relay R⁸⁷ is completed over the following path: battery, R⁸⁷, 422, key k² of strip K¹⁰, 423, second contact of switch 414, wiper 421 to ground. Relay R⁸⁷, upon energization, attracts its armatures locking itself to ground through armature r⁸⁷¹, 424 and contacts of off normal switch 425. The attraction of armature r⁸⁷² completes the circuit of release magnet M⁴², from battery through 425, 426, 427, M⁴² to ground, and the attraction of armature r⁸⁷³ completes the circuit of relay R⁹¹, from battery through r⁹⁴¹ locking wire 418, R⁹¹, 428, r⁸⁷³ to ground. The actuation of the release magnet M⁴² releases the switch 414 and remains energized until said switch assumes its normal or zero position and opens the contacts of off normal switch 425, whereupon relay R⁸⁷ is deenergized, and in turn deenergizes said release magnet. Relay R⁹¹ upon actuation locks its circuit to ground at r⁹¹² and shifts the impulse conductor 420 out of connection with R⁸³ and into series connection with relay R⁸⁴, which connection may be traced as follows: impulse conduc-

tor 420, r⁹¹¹, 429, r⁹²¹, 430, R⁸⁴, 431, r⁸⁷², to battery lead. The actuation of relays R⁸⁷ and R⁹¹ occurs immediately after the second step of the first selector switch, and before the interrupter contacts x have closed, and simultaneously with the completion of the circuit of release magnet M⁴² a battery shifting impulse is sent over the sleeve conductor to actuate the private relay of the first selector, in a manner well known. The circuit of this shifting impulse may be traced as follows: battery, r⁸⁷², 425, 427, r⁸²³, 659 through operator's key 651 (Fig. 1^b) and over sleeve conductor 609 to the circuits of the first selector (Fig. 1^c). This impulse endures during the restoration of the switch 414 and upon its cessation the private magnet is deenergized, and the first selector switch started to test for an idle second selector. During testing the tip and sleeve circuits are opened at the side switch contacts, so that no current can flow through the impulse conductor 420 until after connection is made with a second selector trunk, whereupon the tip circuit is completed through to the circuits of said second selector, and the relays R⁸⁴ (Fig. 1^a) and R⁶⁷ (Fig. 1^c) are intermittently energized, in series, in the same manner as that previously described for relays R⁸³ and R⁶⁴. The circuit of relays R⁸⁴, and R⁶⁷ may be traced as follows: battery, (Fig. 1^a), r⁸¹², 431, R⁸⁴, 430, r⁹²¹, 429, r⁹¹¹, 420, r⁸²², 658, through Fig. 1^b as previously traced, into Fig. 1^c, tip conductor 608, side switch 611, w⁶⁰⁸, 693 and thence through interrupter contacts x and relay R⁶⁷ to ground.

Switch 415 is stepped around in the same manner as was the switch 414 until its wiper 432 engages the fourth contact of its associated bank, whereupon the relay R⁸⁸ is energized, its circuit being from ground through wiper 432, wire 433, key k⁴ of the strip K¹¹, 434, R⁸⁸ through battery lead to battery and back to ground. The energization of R⁸⁸ releases the switch in a manner as before described and completes the circuit of relay R⁹² through the armature r⁸⁸¹, and relay R⁹² in turn opens the circuit of R⁸⁴ at r⁹²¹, and connects the wire 429 to the wire 435, so that the relay R⁸⁹ which controls the third set of number impulses is connected in series with the tip impulse conductor 420 through armature r⁹¹¹, 429, r⁹²¹, 435, r⁹³³, 436, R⁸⁵, 427, r⁸⁸², to battery, which circuit is finally completed upon the deenergization of R⁸⁸ and after the second selector has completed its testing and becomes connected with an idle connector, the test impulse having been sent over the sleeve circuit upon the attraction of armature r⁸⁸². The switch 416 now steps around in synchronism with the primary stepping motion of the connector until the wiper 438 engages the sixth contact of its associated

bank whereupon the circuit shifting relay R^{89} is energized by current from ground through wiper 438, the sixth contact of its associated bank, key k^6 of the strip K^{12} , conductor 439, R^{89} to the battery lead. The relay R^{89} becoming energized, sends the shifting impulse over conductors 426 and 427 through armature r^{892} and energizes R^{93} through r^{891} , and R^{93} in turn shifts the tip circuit from the relay R^{85} to relay R^{86} by the attraction of its armature r^{293} . After the private normal magnet of the connector switch has operated and the side switches stepped to their second position in the usual manner, the relay R^{86} is energized in series with the rotary relay of the connector switch in a manner similar to that described for the other control relays, the connection of R^{86} in series with the tip circuit being from battery lead, through r^{802} , wire 440, R^{86} , 441, 442, r^{293} , 435, and so on as before described. The switch 417 now steps around in synchronism with the secondary or connective movement of the connector switch, and so continues until the wiper 445 engages the third contact when circuit of relay R^{90} is completed from ground through the wiper 445, the third contact of its associated bank, k^3 , 446, R^{90} , and through battery lead to battery B. Relay R^{90} upon energization locks itself through the off normal switch of 417, and connects battery to the impulse wire 426 sending the final test impulse over the sleeve circuit in a manner as before described. The relay R^{90} also connects battery to the locking wire 418 through armature r^{901} and energizes relay R^{94} through armature r^{902} , R^{94} , locking itself to battery through armature r^{824} of the starting relay R^{82} , the latter being held energized on the common locking circuit 418. The attraction of armature r^{942} opens the circuit of R^{86} which brings the wipers of the connector switch to rest on the third contacts of the sixth row which lead to the wanted substation. As the release magnet M^{45} is maintained energized by current over the impulse wire 426, the switch 417 is permitted to move back to its normal or zero position whereupon the off normal contacts of said switch are opened and the relay R^{90} is deenergized. The retraction of armature r^{903} removes battery from the impulse wire 426 which deenergizes the release magnet M^{45} and permits the side switch of the connector to move into the third or final connective position and the attraction of armatures r^{901} and r^{902} removes battery from the common locking wire 418, and opens the energizing circuit of R^{94} respectively. Upon the removal of battery potential from the common locking circuit 418, relays R^{91} , R^{92} , R^{93} and R^{82} are deenergized, and upon the retraction of armature r^{824} of R^{82} , the locking circuit of R^{94} is opened, which then be-

comes deenergized whereupon all the apparatus and circuit of the impulse controlling device are brought to normal condition and the operator is ready for another call.

Referring to Fig. 2, each line circuit 1-2 is provided with a line relay R' and a cut-off relay R^2 which when energized disconnects the line relay R' and connects the tip and sleeve sides of the line to its multiple bank contacts in the primary and connector switches of its group. The attraction of the armature r^{12} of the relay R' connects ground to the individual test contacts of the primary switches S^4 . The attraction of armature r^{11} locks the relay R' on short circuit to ground through armature r^{23} of relay R^2 , which prevents interference by the subscriber in case he should move his receiver hook. The line relays R' are divided into groups of ten and the windings of each group are connected in multiple to the winding of a relay common to the group, which when energized connects ground to the row contact of the primary switch through the armature r^{31} , thus designating the group of lines calling, while the relay R' designates the particular line in the group. Each group of one hundred lines is assumed to have access for calling purposes to ten primary selector trunks, such as shown in Fig. 3, and to be accessible for calling through ten connector switches such as shown in Fig. 4. Thus, each line has twenty sets of multiple contacts, ten in primary selector banks, and ten in the connector banks. The primary distributing switch S determines which trunk in the group of ten being idle, shall respond to any particular call in its group of lines; and one of these primary distributing switches is therefore required for each group of one hundred lines, with its ten trunks. Associated with each primary distributing switch S there is a secondary distributing switch S^2 , and a kick-off switch S' . The function of the secondary distributing switch is to pick out an idle operator's circuit and start the same to testing for the group of primary trunks over which the call originates. This can be done because there being only one switch S^2 for each group of one hundred lines, that is to say for each group of ten trunks such as shown in Fig. 3, and since it is convenient to arrange the contacts of each group of ten trunks in one and the same row in the secondary selector switches S^8 (Fig. 5), each secondary distributing switch can therefore be directly identified with its own associated row of primary trunk contacts in each of the secondary selector switches. The contacts s^{20} are not multiplied but are wired direct to the row contacts s^{82} of the secondary switches S^8 . Number one switch S^2 belonging to a certain group has its first contact s^{20} wired to number one row contact of the first sec-

ondary switch S^8 , its second contact s^{20} wired to number one row contact of the second secondary switch S^8 , and so on. Number two switch S^2 belonging to another group has its 5 first contact s^{20} wired to number two row contact of the first secondary switch S^8 , its second contact s^{20} wired to number two row contact of the second secondary switch S^8 , and so on. In an exchange of one thousand 10 lines the contacts s^{20} of the tenth switch S^2 are wired to number ten row contacts of the secondary switches S^8 . The relay R^5 has one terminal of its winding connected to the wiper arm ws of the switch S . When the 15 arm ws in rotating finds an idle primary switch S^4 the relay R^5 is energized in series with the relay R^{13} (Fig. 3) and opens the circuit of stepping magnet M , thus bringing the switch S to rest. The energizing circuit 20 of relays R^5 and R^{13} may be traced from battery B (Fig. 3), 34, 35, 36, r^{151} , R^{13} , 38 (38 Fig. 2), s , ws , 39, R^5 , 40, r^{42} , to ground. The energizing of the relay R^5 causes the switch S^2 to immediately start to 25 pick out an idle secondary switch S^8 . The switch S^4 can be testing for the calling line while the switch S^8 is testing for the trunk shown in Fig. 3. The relay R^{13} acts somewhat as the line relay R' , connecting battery 30 to its individual test contacts in the switches S^8 .

Referring to Fig. 3, the relay R^{12} is the row test relay, and is energized when the wiper w^{20} finds an active contact, disconnects 35 rotary relay R^{18} and in its place connects vertical relay R^{19} . The relay R^{15} is used in testing for the individual contact as well as a battery supply relay for the calling subscriber. When energized this relay 40 disconnects the row relay R^{12} . The deenergizing of relay R^{12} disconnects the relay R^{15} from the test wiper w^{25} and connects it to the sleeve wiper w^4 in series with the cut-off relay R^2 . Relay R^{14} is the tip battery supply relay and controls the release magnets M^3 and M^4 after the first selector switch S^5 has moved off-normal. The relay R^{42} is used for opening the talking circuit while the impulses are being sent to operate the 45 outgoing switches. This relay also with R^{15} jointly controls the relay R^{13} . Relay R^{41} is the test relay having its locking contact r^{413} connected to the test wiper w^{147} . Its circuit is initially closed through the contacts of 50 relay R^{42} and foot springs 144 and 145. After the switch S^5 makes its first vertical step the circuit of this relay is maintained through contacts of relay R^{42} and test wiper w^{147} so long as this wiper encounters busy 55 contacts, which are grounded through other switches.

Referring to Fig. 4, relays R^{22} and R^{23} are impulse relays reciprocally controlling and controlled by magnets M^9 and M^{10} . Relay R^{23} provides the first set of impulses be-

longing to the connector and causes the stepping magnet M^{11} of the switch S^7 to step around so as to pick out generator current of the proper character, each actuation of relay R^{23} making the circuit of magnet M^{11} 70 and each actuation of this magnet breaking the circuit of relay R^{23} so a continuous stepping is produced and impulses are also sent back to the key-set. Operation of relay R^{23} closes the circuit of relay R^{24} whose locking contact r^{241} is connected to the back contact of relay R^{22} . Relay R^{23} also closes circuit of relay R^{27} . This latter remains energized until the called party answers or until the calling party hangs up his receiver. In case 80 the called-for line is busy, relay R^{27} will be deenergized by action of test relay R^{29} . Relays R^{24} , R^{27} and R^{29} all have their circuits completed to ground side of battery through test wire 200, contacts c^{200} , w^{147} , r^{413} to 85 ground. When the calling party hangs up his receiver after failing to get his party, switches S^4 and S^5 are restored and ground removed from test wire, causing deenergization of any of the relays R^{24} or R^{29} which 90 happen to be locked. The switch S^7 is restored to normal after the called subscriber hangs up his receiver or when the relays R^{25} , R^{27} and R^{24} are deenergized; and just before it reaches its normal position the 95 wiper arm ws^7 passes over a contact and closes the circuit of the release magnet M^{12} restoring the connector switch S^6 to normal position. Thus the connector switch S^6 has a quick release if the called-for line is busy, 100 and after the called party answers a slow release by switch S^7 .

Referring to Fig. 5 relay R^{31} is the row test relay and R^{30} the individual test relay. Relay R^{32} is the control relay and corresponds to relay R^{13} (Fig. 3). Relay R^{34} is the signal relay and pulls up in series with relay R^{42} (Fig. 3) after the primary trunk has found the line and the secondary switch S^8 has found the trunk. The operation of 105 this relay closes the circuits of the signal lamp L^3 (Fig. 6), the guard lamp L^2 and the night alarm bell. Relay R^{33} is the listening relay actuated by listening key LK . Operation of this relay deenergizes relays 110 R^{34} and R^{42} and closes circuit of listening lamp L^4 . Relay R^{36} is the starting relay and is energized in series with R^{42} by the key SK . This relay disconnects relay R^{33} 115 and connects the starting contact on the impulse receiver to stepping magnet M^{15} . It also closes circuit of guard lamp L^2 and disconnects battery from the first five contacts over which wiper ws^{300} sweeps. After arm ws^{300} passes the fifth contact it encounters 120 battery potential and relay R^{35} is energized and connects interrupter I to magnet M^{15} until arm ws^{300} reaches its normal position. Just before switch S^3 reaches normal position, cam springs 167, 168 are closed, com- 125 130

pleting the circuit of release magnet M^4 , restoring switch S^8 to its normal position. Relay R^{37} is the trunk start relay and is also used for release in case the calling subscriber 5 has hung up his receiver or if the operator fails to get a response after pressing the listening key. This relay R^{37} is energized by key RK , which also actuates relay R^{36} . These two relays being energized at the same 10 time remove battery connection from the first two contacts over which arm ws^{300} sweeps. The first selector switch S^5 upon receiving the first rotary impulse through one of the buttons of the strip K' closes the 15 foot springs 175 and 176. The closure of these springs while relay R^{14} is deenergized completes the circuit of release magnets M^2 and M^4 causing the release of switches S^4 and S^5 . 20 Referring to Fig. 6, number one key of each strip is connected to the first contact on the impulse receiver S^{14} which takes one step at each impulse sent back from the switches; number two key to the second contact, and 25 so on to number ten key which is connected to the tenth contact. Each strip of keys has a common wire connected to one contact of each key in the strip and leading to its proper contact on one or the other of the 30 controlling relays associated with switch S^3 . The order in which these are arranged to transmit impulses in proper sequence is as follows: At the first rotation of the impulse receiver the first strip of keys (hundreds) is 35 connected to the tip side of the trunk; second rotation, ten test impulses to impulse receiver over sleeve side of trunk, third rotation, selective ringing strip K^4 connected to tip side of trunk; fourth rotation, keys 40 K^2 (tens) connected to sleeve side; fifth rotation, keys K^3 (units) connected to tip side of trunk; during the fifth rotation and just after the units impulses have been sent, a single test impulse is sent to sleeve side of 45 trunk; sixth rotation, arm ws^{300} engages contacts connected to battery energizing relay R^{35} . This relay unlocks R^{36} restores switches S^3 and S^8 , thus disconnecting secondary switch S^8 from the primary trunk in 50 Fig. 3.

The operation of the circuits shown in Figs. 2, 3, 4, 5 and 6 is as follows: The subscriber at station A desiring a connection lifts receiver R from hook H which bridges his telephone across line wires 1-2, energizing relays R^1 and R^3 by way of B, 19, 55 20, R^3 , 21, R^1 , 22, R^{21} , I, station A, 2, r^{22} , 23, ground to battery. Relay R^1 locks to ground through r^{11} , 24, and r^{23} , and connects ground 60 to individual test contact c^{25} through 25 and r^{12} , while R^3 connects ground to row test contact c^{26} through 26 and r^{31} and completes circuit of group lamp L and relay R^4 the former from B, 19, 27, L, 28, r^{32} , ground to battery, the latter from B, 19, 29, R^4 , 30, r^{33} , 65 to ground. Lamp L lights, and relay R^4 completes circuit of stepping magnet M to interrupter I for intermittent energization over the path B, 19, M, 31, r^{51} , 32, r^{41} , 33, I to ground. Magnet M moves switch S step 70 by step until wiper ws engages a contact connected to relay R^{13} (Fig. 3) of an idle primary selector trunk, whereupon relays R^5 and R^{13} (Figs. 2 and 3), are energized by current through B (Fig. 3), 34, 35, 36, r^{151} , 75 37, R^{11} , 38, (38 Fig. 2), s , ws , 39, R^5 , 40, r^{42} , to ground. Relay R^5 opens circuit of magnet M at r^{52} , locks itself to ground through r^{52} and completes circuit of R^{11} over path B, 19, 41, R^{11} , 42, R^{53} and ground. Relay R^{13} 80 locks itself to battery through r^{131} , 43, r^{121} , 44, and 34 to B; connects battery to one terminal of relay R^{12} , through 34, 35, r^{133} , 45, 46, r^{152} , 47, and 48; and also completes circuit of rotary relay R^{18} through r^{132} and interrupter I, so that this relay is energized intermittently its circuit being; B, 34, 35, r^{133} , 45, 46, r^{152} , 47, 49, 50, R^{18} , 51, r^{121} , 52, r^{132} , I to ground. At each actuation of relay R^{18} magnet M^5 is energized by current from B, 90 34, 57, contacts 58 of foot step switch F^4 , 59, M^5 , 53, r^{181} , ground, stepping primary selector switch S^4 around until wiper w^{26} engages row test contact c^{26} whereupon relay R^{12} is energized over circuit B (Fig. 3), 34, 95 35, r^{133} , 45, 46, r^{152} , 47, 48, R^{12} , 49, w^{26} , c^{26} (Fig. 2), 26, r^{31} , ground to battery. Relay R^{12} locks itself to ground through r^{122} , connects test wiper w^{25} to sleeve relay R^{16} through 54, r^{123} and 55, and shifts interrupter I from rotary relay R^{18} to vertical relay R^{19} at r^{121} , so that R^{19} is intermittently energized over the circuit; B, 34, 35, r^{133} , 45, 46, r^{152} , 47, 49, R^{19} , 56, r^{121} , 52, r^{132} , I ground to battery. At each actuation of relay R^{19} 100 vertical magnet M^6 is energized over the path B, 34, 60, M^6 , 61, r^{101} to ground, stepping switch S^4 up until wiper w^{25} engages individual test contact c^{25} (Fig. 2) whereupon sleeve relay R^{16} is energized over the 105 circuit; B (Fig. 3), 34, 35, R^{15} , 55, r^{123} , 54, w^{25} , c^{25} , (Fig. 2), 25, r^{12} (of relay R^1), ground to battery. Relay R^{15} connects battery to trunk conductor 7, by way of r^{151} , 63, 110 64, r^{141} , 65, and resistance r , and at the same time opens the circuit of relay R^{12} at r^{152} . Relay R^{12} opens circuit of vertical relay R^{11} and magnet M^6 is deenergized, which permits wiper w^{25} to stop on contact c^{26} , wipers w^3 and w^4 engaging contacts c^3 and c^4 , respectively. Tip relay R^{14} is now energized through subscriber's telephone in series with R^{15} . Simultaneously with the selection of the calling line as described, distributing switch S^2 (Fig. 2), is stepped around in 115 search of an idle secondary selector, by magnet M^2 in circuit: B, 19, 41, 66, 67, 68, r^{91} , 69, M^2 , 70, r^{111} , 71, I to ground. Switch S^2 continues to step around until wiper arm ws^{200} 120 engages a contact s^{200} connected to an idle 125 65 battery, the latter from B, 19, 29, R^4 , 30, r^{33} , 130

secondary selector, whereupon relays R^{10} and R^{32} (Figs. 2 and 5) are energized in series, the circuit being: B (Fig. 5), 86, springs 73-74 of operator's jack J, 75, 5 springs 76-77 of foot step switch F^s , 78, R^{32} , 79, through Fig. 3 into Figs. 2, s^{200} , 80, 81, R^{10} , 82, r^{112} to ground. The actuation of relay R^{10} causes the energization of relay R^9 , the circuit being: B, 19, 41, 66, 10 67, r^{101} , 83, 84, R^9 , 85, r^{113} to ground. Relay R^9 locks itself to battery through r^{92} , and 15 opens circuit of magnet M^2 at r^{91} , whereupon switch S^2 comes to rest with wiper arms ws^{22} , ws^{20} and ws^{200} resting on contacts s^2 , s^{20} and s^{200} , respectively.

The attraction of armature r^{91} of relay R^9 connects battery to wire 99, which completes part of the row test circuit, and the attraction of armature r^{93} completes the 20 circuit of relay R^8 as follows: B to R^8 , 223, r^{93} to ground. Relay R^8 grounds wire 80, shunting relay R^{10} out of series with relay R^{32} (Fig. 5), the circuit of the latter relay now going direct to ground by way of wire 25 80 and armature r^{82} . Relay R^{32} (Fig. 5) completes the circuit of rotary relay R^{39} through interrupter I, so that said relay is intermittently energized by current over B, 30 86, 87, r^{301} , 88, r^{311} , 89, R^{39} , 90, r^{321} , I to ground. Relay R^{32} also connects one terminal of relay R^{30} to ground through 91 and r^{322} , and locks itself to battery through 35 92, r^{323} , 93, r^{302} , 87, 86, B. Each actuation of relay R^{39} energizes rotary magnet M^{13} through B, 86, 94, M^{13} , 95, r^{391} to ground. Magnet M^{13} steps switch S^8 around until wiper w^{82} engages contact s^{82} . The first rotary step of the switch S^8 disconnects contacts 76 and 77 of switch 40 F^s and connects contacts 76 and 290, which opens the initial energizing circuit of relay R^{32} , (that relay, however, remaining energized through its locking circuit), and 45 closes the circuit of off-normal lamp L^7 as follows: B, 86, 73, 74, 75, 76, 290, L^7 to ground. When wiper w^{82} engages contact s^{82} the relay R^{31} is energized over the path: B, ground to r^{322} (of relay R^{32}), 91, 96, R^{31} , 97, w^{82} , s^{82} , 98, through Fig. 3 into Fig. 2, 50 s^{20} (in switch S^2), ws^{20} , 99, r^{91} , 68, 67, 66, 41, 19, battery. Relay R^{31} locks itself to battery through: 100, r^{312} , 101, 88, r^{301} , 87 and 86, opens circuit of relay R^{39} and closes circuit 55 of relay R^{40} at r^{311} . Relay R^{39} opens circuit of magnet M^{13} at r^{391} , which stops switch S^8 with wiper w^{82} engaging contact s^{82} . As circuit of relay R^{40} is completed at r^{311} said relay is intermittently energized through: B, 86, 87, r^{301} , 88, r^{311} , 102, R^{40} , 103, 90, r^{321} , I, ground. Each actuation of relay R^{40} energizes vertical magnet M^{14} through: B, 86, M^{14} , 104, r^{401} , ground. Magnet M^{14} steps switch S^8 up until wiper w^{84} engages contact s^{84} , whereupon relay R^{30} is energized through: B, ground to r^{322} (relay R^{32}), 91,

R^{30} , 105, w^{84} , s^{84} , 45 (45, Fig. 3), r^{133} , 35, 34, battery. Relay R^{30} opens locking circuit of relay R^{32} at r^{302} , also opens circuit of relay R^{40} at r^{301} . r^{401} of relay R^{40} opens circuit of vertical magnet M^{14} , which stops switch S^8 70 with wipers w^{80} , w^{81} , w^{83} and w^{84} on contacts s^{80} , s^{81} , s^{83} and s^{84} . (Wiper w^{82} is raised off row contacts by first step). Wiper w^{83} engaging contact s^{83} , (Fig. 5) relays R^{34} and R^{42} , (Figs. 5 and 3) are energized through: B, (Fig. 3), 34, 35, 36, r^{161} , 63, 106^a, R^{42} , 107, (107 Fig. 5), s^{83} , w^{83} , 108, r^{313} , 109, r^{351} , 111, 112, R^{34} , 113, r^{331} , 114, r^{361} , 115, r^{352} , 116, r^{322} , ground. Relay R^{42} , when actuated, opens series circuit of relays 80 R^5 and R^{13} (Figs. 2 and 3) at r^{421} . Relay R^{13} disconnects interrupter I at r^{132} and relay R^5 (Fig. 2) opens circuit of relay R^{11} at r^{53} . Relay R^{11} deenergizing opens circuits of magnet M^2 , relay R^9 and relay R^{10} , 85 while relay R^8 , its circuit opened at r^{93} , opens circuit of stepping magnet M^1 at r^{61} . This prepares distributing switches, S and S^2 , with their relays, for another call. Relay R^{34} becoming energized closes circuit of 90 night alarm W through: B, 86, 110, 117, 118, r^{341} , 119, W, to ground; closes circuit of guard lamp L^2 (Fig. 6) through B (Fig. 5), 86, 110, 117, 118, r^{342} , 120, 121 (121 Fig. 5), L^2 to ground; closes circuits of service 95 meter E (Fig. 5) through B, armature r^{343} , 122, 242, and magnet of service meter E to ground; and line lamp L^3 (Fig. 6) through B (Fig. 5) r^{343} , 122, 123 (123 Fig. 6), L^3 to ground. The operator, perceiving the 100 signal, depresses listening key LK (Fig. 6) energizing listening relay R^{33} (Fig. 5) through: B (Fig. 5), 86, 87, r^{301} , 88, 101, r^{312} , 124, R^{33} , 125 (125 Fig. 6), contacts of key LK, to ground. Relay R^{33} energizing, 105 opens series circuit of relays R^{34} and R^{42} at r^{331} and locks itself to ground through r^{331} , and 114, as previously traced. Relay R^{42} deenergizing, opens circuit of relay R^{41} at r^{421} . Relay R^{33} completes the operator's listening circuit as follows: receiver OR, 127, 110 plug P, tip P', spring j , 128, r^{333} , 129, 131, w^{80} , s^{80} , 130 (130 Fig. 3), r^{411} , 133, 9, 422, 7, condenser C^1 , 5, w^3 , c^3 (Fig. 2), 3, r^{21} , line wire 1, subscriber's telephone, line wire 2, 115 r^{22} , 4, c^4 , w^4 , (Fig. 3), 6, condenser C^2 , 8, r^{423} , 10, 134, r^{412} , 135 (135 Fig. 5), s^{81} , w^{81} , 132, 136, r^{332} , 137, coil IC, 138, jack spring j^1 , plug sleeve p^1 , 139, receiver OR. The operator, on ascertaining the number wanted sets up the same on her key set, 120 (Fig. 6), by depressing the key in strip K^1 corresponding to the first digit, that in the strip K^2 corresponding to the second digit, that in the third strip K^3 corresponding to the third digit, and that in the strip K^4 corresponding to the particular ringing generator to be selected, and then actuates 125 starting key, SK, whereupon starting relay R^{36} (Fig. 5) is energized in series with 130

trunk cut-off relay R^{42} (Fig. 3) through: ground, 126, (Fig. 6) key SK , 140, (140 Fig. 5) R^{36} , 141, 111, r^{351} , 109, r^{313} , 108, w^{83} , 83, 107, (107 Fig. 3), R^{42} , 106, 63, r^{151} , 35, 5 34, battery to ground. Relay R^{42} opens trunk conductors 9-7 and 10-8 at r^{422} and r^{423} , and energizes relay R^{41} through: B, 34, 44, r^{211} , 142, R^{41} , 143, contacts 144 and 145 of switch F^6 to ground. Armatures 10 r^{411} and r^{412} connect the impulse wires 130 and 135 to rotary and vertical relays R^{21} and R^{20} , respectively, while armature r^{413} connects conductor 147 to one terminal of relay R^{41} through contact 146. Starting relay 15 R^{36} (Fig. 5) takes ground off relay R^{33} through 114, at r^{361} , and locks itself through 148, 361 and 115 to ground as previously traced. Armature r^{363} connects starting wire 151 to stepping magnet M^{15} through: 20 B, (Fig. 5) 86, 110, 117, M^{15} , 153, r^{363} , 152, r^{363} , starting wire 151, (151 Fig. 6) contact d^{11} to ground; so that said magnet is momentarily energized, stepping switch S^3 forward one step. This first step of the switch 25 S^3 brings the wipers ws^3 , ws^{30} and ws^{300} into engagement with the first contact $1s^3$, etc., of their respective banks. The wiper arm ws^{30} connects ground to the common wire 405 of key strip K^1 (Fig. 6), and relay 30 R^{53} (Fig. 5) is energized by current from B, 86, ws^3 , $1s^3$, 401, 402, R^{53} to ground. The actuation of R^{53} connects the tip conductor 131, to the common impulse conductor 403 at r^{531} , which completes the circuit 35 of relay R^{21} (Fig. 3) over the following path: B (Fig. 3), 34, 60, 194, R^{21} , m^8 , 174, r^{211} , 130, 130 (Fig. 5), s^{80} , w^{80} , 131, r^{531} , 403, 403 (Fig. 6), R^{78} , 404, r^{791} to ground. Relay R^{21} upon actuation completes the circuit 40 of rotary magnet M^8 which upon actuation steps the switch spindle and wipers around one step and at the end of its stroke opens the circuit of relay R^{21} at m^8 . R^{21} becoming deenergized opens the circuit of 45 M^8 which upon deenergization closes the former circuit of R^{21} which again becomes energized and again closes circuit of M^8 , and so on, the stepping of the switch spindle and the breaking and making of the circuit 50 of R^{21} continuing as long as the wire 404 (Fig. 6) remains grounded through armature r^{791} . As the relays R^{21} (Fig. 3) and R^{78} (Fig. 6) are in series, each time the relay R^{21} is energized the relay R^{78} is energized and completes the energizing circuit 55 of stepping magnet M^{37} of switch S^{14} at armature contact r^{781} , stepping the switch arms s^{141} , s^{142} and s^{143} around one step at each step of the selector switch S^5 . Assuming that the digits set up on the key strips K^1 , K^2 , K^3 and K^4 are 2, 4, 6 and 3 respectively, the switches S^5 and S^{14} will continue to step around in synchronism until the wiper s^{143} of switch S^{14} engages contact d^2 60 whereupon relay R^{79} is energized by current over the following path: B, R^{79} , 406, s^{143} , d^2 , 407, 408, k^2 , 405, 405 (Fig. 5) switch arm ws^{30} to ground. The relay R^{79} upon energization attracts its armatures r^{791} , r^{792} and r^{793} locking its circuit through 70 409, r^{792} , 410 to ground through restoring contacts d^8 and arm s^{141} . The attraction of armature r^{791} , opens the series circuit of relays R^{21} (Fig. 3) and R^{78} (Fig. 6) which brings the switch S^5 to rest with its wipers beneath 75 the second row of contacts and opens the energizing circuit of M^{37} (Fig. 6) at r^{781} . The attraction of armature r^{793} completes the circuit of M^{37} through interrupter I so that the switch S^{14} continues to step around until 80 the wiper arms s^{141} , s^{142} , etc., assume the normal or zero position as shown when the locking circuit of relay R^{79} is interrupted between contacts d^8 and arm s^{141} and relay R^{79} releasing its armatures again opens the in- 85 termittent circuit of M^{37} at r^{793} . At the first rotary step of switch S^5 contact springs 175-176 are closed, partially closing the release circuit through magnets M^3 and M^4 . When the switch S^{14} assumes the position 90 shown, the arm s^{142} again engages contact d^{11} again energizing magnet M^{15} (Fig. 5) which steps the wiper arms ws^3 , ws^{30} , etc., around into engagement with the second contact of 95 their respective banks. The wire 411 is connected to ground through wiper arm ws^{30} which energizes relay R^{80} (Fig. 6). The actuation of R^{80} connects conductor 412 to ground through r^{801} , and connects conductor 406 to ground at r^{802} which energizes relay R^{79} . 100 The relay R^{79} upon actuation locks itself and maintains the continued operation of the switch S^{14} around to normal position in a manner as before described. 105 Simultaneously with the energization of relay R^{80} , the relay R^{81} is energized by current from B, 86, ws^3 , $2s^3$, 412, R^{81} to ground. The actuation of relay R^{81} connects the conductor 132 to conductor 403, and the energizing circuit of relay R^{20} (Fig. 3) is completed as follows: B, R^{20} , 199, r^{412} , 135, 135 (Fig. 5) s^{81} , w^{81} , 132, contact of R^{81} , 403, 403 (Fig. 6) to ground through r^{801} . Relay R^{20} and vertical magnet M^7 are now intermittently actuated to step up the spindle of 110 switch S^5 in the same manner as R^{21} and M^8 operated to step it around, the stepping up continuing so long as the relay R^{41} remains energized. At the first vertical movement of the spindle of switch S^5 the circuit of relay R^{41} is opened at contact springs 144 and 145 of switch F^6 , and should the connector 115 trunk (Fig. 4) be busy because of the wipers of another first selector switch resting on the multiples of contacts c^{200} , relay R^{41} would remain energized through: B (Fig. 3), 34, 44, r^{421} , 142, R^{41} , 146, r^{413} , 147, w^{147} , c^{200} (Fig. 4) to the multiples of c^{200} and thence through the circuit of the other first 120 selector by way of its wiper w^{147} (as in 130

Fig. 3), 147, r^{413} , ground, to battery. The armature r^{412} of relay R^{41} , remaining attracted permits the vertical relay R^{20} and magnet M^7 to step the wipers up to the next 5 set of contacts, and so on until an idle connector is reached, when, relay R^{41} being deprived of ground, releases its armatures. The armature r^{412} disconnects wire 135 from the relay R^{20} , stopping switch S^5 with its 10 wipers w^9 , w^{10} and w^{147} on contacts c^{13} , c^{14} and c^{200} , respectively, of the connector trunk (Fig. 4). The wires 130 and 135 are now connected to the tip and sleeve conductors 9 and 10 through armatures r^{411} and r^{412} , respectively, and contact c^{200} (Fig. 4) and its 15 multiples are connected to ground through w^{147} (Fig. 3), 147 and r^{413} . The switch S^{14} upon assuming its normal position again completes the circuit of magnet M^{15} through 20 contact d^{11} and wiper arm s^{142} , and steps switch S^3 around to bring its wipers into engagement with the third set of contacts. Ground is now connected through wiper 25 ws^{30} to wire 430 common to the keys of strip K^4 and the circuit of relay R^{53} is closed through wiper ws^3 and wires 401—402. The actuation of R^{53} completes the circuit 30 of relay R^{23} (Fig. 4) and R^{78} (Fig. 6) in series over the following path: B (Fig. 4), R^{23} , 444, m^{10} , 443, m^{11} , 204, r^{261} , 16, c^{13} , w^9 (Fig. 3), 9, 133, r^{411} , 130, 130 (Fig. 5), s^{80} — w^{80} , 131, r^{531} , 403, 403 (Fig. 6) R^{78} , 404, and to ground through r^{701} . The attraction of armature r^{231} , completes the circuit of stepping magnet M^{11} , which circuit may be traced from ground at armature r^{231} , of R^{23} , 215, 214, M^{11} , 213, 212 and through off normal springs 211—210 and battery lead to battery B. The magnet M^{11} upon actuation 40 steps the generator selector switch around one step and at the completion of this operation opens the circuit of relay R^{23} at m^{11} . The relay R^{23} becoming deenergized opens circuit of M^{11} which latter upon deenergization again closes circuit of R^{23} and this 45 cycle of operations is continuously repeated, causing the switches S^7 and S^{14} (Fig. 6) to step in synchronism, until the wiper s^{143} engages the third contact d^3 which completes the circuit of relay R^{79} . This circuit may be traced from battery B, through R^{79} , 406, s^{143} , d^3 , 431, k^3 , 430, 430 (Fig. 5) to ground through wiper sw^{30} . Relay R^{79} is now energized and opens the series circuit of R^{78} 50 and R^{23} which causes the switch S^7 to come to rest with its wipers s^{141} , s^{142} and s^{143} in engagement with the third contact of their respective rows, while the relay R^{79} is held energized in a locking circuit through wiper s^{141} of S^{14} and maintains the continuous movement of the switch S^{14} until it reaches its normal or zero position, in the same manner as before described, which results 55 in the deenergization of the relay R^{79} . The first actuation of relay R^{23} energizes R^{24}

and R^{27} , the first through: B, 207, r^{233} , 247, R^{24} , 202, 200, c^{200} , w^{147} , (Fig. 3) 147, r^{413} to ground, locking itself to battery through 249, r^{241} , 250, r^{222} , 207; the second relay through: armature r^{232} , 230, R^{27} , 235, r^{262} , 70 236, 202, to ground, locking itself to battery through: 232, r^{271} , 233, r^{201} , 231.

The switch S^{14} upon assuming its zero position again energizes magnet M^{15} (Fig. 5) which steps the wiper arms of switch S^3 75 around into engagement with the fourth contact, whereupon ground is connected through wiper ws^{30} to wire 447, common to the keys of strip K^3 , and relay R^{81} is energized through wiper ws^3 and wire 412. R^{81} , 80 upon energization connects the relay R^{78} , (Fig. 6) and R^{22} (Fig. 4) in series. This circuit may be traced from battery B (Fig. 4), battery lead 231, armature r^{261} , 233, r^{271} , 232, 230, R^{22} , 448, m^9 , 228, r^{262} , 15, c^{14} , w^{10} , 85 (Fig. 3) 10, 134, r^{412} , 135, and thence through the sleeve circuit of the operator's control circuit (Fig. 5) and through relay R^{78} (Fig. 6) as before described. The actuation of relay R^{22} (Fig. 4) energizes magnet M^9 by completion of the following circuit: ground at armature, r^{221} , 240, M^9 , 239, off-normal contact springs 238—237 to battery. The magnet M^9 and relay R^{22} now operate to step switch S^6 around to the desired row of contacts, in a manner similar to that in which the magnet M^{11} and relay R^{23} operate to step switch S^7 , the switches S^{14} and S^6 stepping in synchronism until wiper s^{143} of S^{14} 90 engages contact d^6 which completes the circuit of relay R^{79} through key k^4 of strip K^2 and brings the wiper of the connector switch S^6 to rest opposite the fourth row of contacts, while switch S^{14} continues to step to zero position, all in a manner as before described. The first actuation of R^{22} opens the locking circuit of R^{24} at r^{222} . The first rotary step of switch S^6 opens springs 210—211 95 and closes 210—246, which shifts battery lead 209 from M^{11} to M^{10} . When the switch S^{14} again assumes its zero position the magnet M^{15} (Fig. 5) is again energized stepping the wipers of switch S^3 around into engagement with their fifth contact, which connects ground to wire 449, common to the keys of strip K^3 , through wiper ws^{30} and energizes relay R^{82} through wiper ws^3 and wire 450. The actuation of R^{82} connects the sleeve conductor 132 to wire 451 leading to the contact d^{11} of S^{14} , and connects battery 100 lead to wire 402 which energizes relay R^{53} , the latter relay upon actuation connecting the tip conductor 131 to wire 403. Relays R^{78} (Fig. 6) and R^{23} are again energized in series in the same circuit as previously traced, the vertical magnet M^{10} now operating with the relay R^{23} in the same manner in which magnet M^{11} operated therewith, the circuit of magnet M^{10} being traced from: 105 battery lead through off-normal contacts 110

battery lead through off-normal contacts 115

120

125

130

- 210—246, 245, 244, M^{10} , 243, r^{272} , 215, r^{231} , to ground. The relays R^{23} and magnet M^{10} now operate to step the spindle of switch S^6 vertically, the switch S^{14} (Fig. 6) stepping 5 in synchronism therewith until the wiper s^{142} of S^{14} engages the sixth contact d^6 which completes the energizing circuit of relay R^{29} through contact d^6 , contacts of key k^6 of strip K^3 and wiper ws^{30} of S^3 . The 10 actuation of R^{29} causes the connector switch S^6 to come to rest with its wipers in engagement with the sixth set of contacts in the fourth row leading to the wanted substation, while S^{14} continues to step around to 15 zero position, as before described. The first actuation of relay R^{23} again energizes R^{24} through: r^{233} and R^{24} locks itself disconnecting R^{25} and R^{26} from wipers w^{17} and w^{18} , at r^{243} and r^{241} to prevent affecting said relays 20 while the wipers were passing over other line multiples.
- When the wiper s^{142} of S^{14} engages contact d^{12} , a single test impulse is sent over the sleeve circuit from ground through wiper 25 s^{142} , contact d^{12} and over wire 451, 451 (Fig. 5), sleeve conductor 132 and so on to relay R^{22} (Fig. 4) as previously traced, whereupon if the wanted line is busy, with wipers w^{17} , w^{18} , of another connector switch, or w^3 , 30 w^4 of a primary selector switch, resting on multiples of contacts c^{17} , c^{18} , the test relay R^{29} (Fig. 4) is energized, in the first case through: ground, r^{413} (Fig. 3), 147, w^{147} , c^{200} (Fig. 4), 200, 201, R^{29} , 251, r^{223} , 252, r^{281} , 253, 35 18, w^{18} , c^{18} , (see Fig. 2, the circuits of the called line being the same), to the multiple of c^{18} on which the other connector switch wipers are resting, thence through that connector (see again Fig. 6, this connector link 40 being the same) by way of w^{18} , 18, 253, r^{281} , 252, r^{223} , 259, R^{26} , 260, 261, r^{241} , 250, r^{222} , 207, B, to ground; in the second case through: ground, R^{29} , c^{18} , thence through the multiple 45 of c^{18} on which wiper w^4 , of a primary selector is resting, 294, r^{123} , 55, R^{16} , 35, 34, B to ground. Relay R^{29} when energized locks itself to battery through: 262, r^{291} , connects the busy back B_2 to trunk conductor 16, through r^{292} and 263, and closes the release 50 circuit of S^6 through: B, 206, 208, 209, 210, 246, 245, 264, 265, r^{293} , 267, 269, M^{12} to ground. M^{12} then releases the connector switch S^6 . After this impulse relay R^{29} is deenergized, 55 and completes the restoring circuit of switch S^7 through: B, r^{222} , 250, r^{241} , 261, 270, r^{278} , 271, r^{251} , 272, 213, M^{11} , 214, r^{272} , 273, ws^{700} , s^{700} , 274, I to ground. Magnet M^{11} is intermittently energized until switch S^7 reaches normal position when its circuit is opened 60 between ws^{700} and s^{700} . The test relay R^{29} remains locked, holding busy-back B_2 on trunk conductor 16, to signal the calling subscriber (Fig. 2), who then hangs up his receiver, opening circuit of R^{14} (Fig. 3) 65 which deenergizes and energizes magnets M^3 and M^4 of switches S^4 and S^5 through ground, 175, 176, 106, 177, r^{142} , 178, 179, M^3 and M^4 (in multiple), B, to ground. The switch S^5 in restoring opens the circuit of R^{29} (Fig. 4) at c^{200} and w^{47} (Fig. 3) and the 70 busy-back is disconnected.
- If the wanted subscriber is not busy, R^{27} remains locked, and after the test impulse R^{22} deenergizes, which energizes R^{26} (Fig. 4) and R^{43} (Fig. 7) in series, through: B 75 (Fig. 4), r^{222} , 250, r^{241} , 261, 260, R^{26} , 259, r^{223} , 252, r^{281} , 253, 18, w^{18} , c^{18} (Fig. 2), 4, cut-off relay R^2 to ground. Relay R^{26} closes contacts r^{262} and mate, and r^{261} and mate, so as to connect the trunk conductors 15 and 16 to 80 their extensions, 17 and 18, respectively. Simultaneously with the energization of R^{26} and R^2 , ringing relay R^{28} is connected through: B, r^{222} , 250, r^{241} , 261, 270, r^{273} , 277, r^{242} , 278, R^{28} , interrupter I^2 to ground. Immediately after the test impulse, the switch 85 S^{14} arrives at its normal or zero position, and wiper s^{142} engaging contact d^{11} , sends an impulse over wire 151, stepping switch S^3 (Fig. 5) forward one step bringing its wipers onto the sixth contact set. When ws^{300} engages contact $6s^{300}$, the restoring relay R^{35} 90 is energized through: B, 86, 110, 166, $6s^{300}$ to $9s^{300}$, ws^{300} , 164, R^{35} to ground. Relay R^{35} opens circuit of R^{36} and R^{42} (Figs. 5 and 3 95 respectively), at r^{351} and r^{352} , while r^{353} connects magnet M^{15} for intermittent energization through: B, 86, 110, 117, M^{15} , 153, 165, I to ground. Magnet M^{15} steps switch S^3 forward, holding R^{35} energized through 100 ws^{300} and contacts $6s^{300}$ to $9s^{300}$, until the wipers have reached normal position, as shown. The secondary selector switch S^8 is restored by the cam on the switch S^3 , in passing, and the operator's circuit is ready 105 to receive another call.
- I have shown and described the best embodiment of my invention now known to me but it is obvious that my invention may be variously embodied by those skilled in the 110 art without in any wise departing from its generic spirit, and I therefore wish to cover by the annexed claims all such modifications to which by my invention I am legally entitled to cover.
- Having thus described my invention, 115 what I claim and desire to secure by Letters Patent is:—
1. In a telephone exchange system, a plurality of links containing automatic switches and adapted to be connected in series to join a pair of lines for conversation, a motor without the links and means to connect the motor with one of the links for operation in synchronism with a connected automatic 120 switch, means determining the extent of operation of the automatic switch of a connected link in synchronism with the said motor, means thereupon becoming active to return the motor to normal by continued 125
- 130

movement in the same direction, and motor control connections governed by said motor in its return to normal movement and by the automatic switch of the connected link 5 to place the said motor in synchronous operative condition with respect to an automatic switch of a succeeding link.

2. In a telephone exchange system, subscribers' lines, and connective links having 10 automatic switches for interconnecting the lines, an impulse device in each switch, a synchronous controller associated with the links and adapted to be stepped always in the same direction, with means to connect 15 said controller with an impulse device so as to be stepped thereby in synchronism with the associated automatic switch, and in the same direction, whereby the position of said automatic switch may be selectively 20 determined.

3. In a telephone exchange system, a plurality of lines, automatic switches and circuits for interconnecting the same, an impulse device in each switch, a motor adapted 25 to be stepped by the impulse device in synchronism with an automatic switch in one direction only, together with means to connect said motor singly with any one of the connective circuits, and devices selectively 30 limiting the forward movement of the motor in synchronism with the automatic switch of any connective circuit with which it is for the time being connected.

4. In a telephone exchange system, a plurality of lines, connective links having automatic switches for interconnecting said lines, a motor associated with said links and adapted for synchronous movement with the automatic switch of any link in one direction 35 only, and selectively adjustable circuit controlling means forming part of and governed by said motor in its movement, with means for adjusting said circuit controlling means to stop said automatic switch 40 at a predetermined point.

5. In a telephone exchange system, a plurality of lines, connective links having automatic switches for interconnecting said lines, and a motor controller associated with the 50 links and having a movement by successive steps in one direction only, motor control connections whereby movement of said motor in the initial stage takes place in response to and in synchronism with the 55 movement of an automatic switch of a link, and additional control connections governed by and governing the motor in its movement whereby said movement in subsequent stages is in a synchronism with the automatic 60 switch.

6. In a telephone exchange system, a plurality of lines, connective links containing automatic switches for interconnecting said lines, a single motor controller associated 65 with said links and adapted to operate in

synchronism with each of several automatic switches in successive links, operating connections between each switch and the motor, controlled by the automatic switch to effect the synchronous operation, and connections 70 controlled by the motor to determine the extent of travel in the synchronous operation.

7. In a telephone exchange system, a plurality of lines, connective links having automatic switches for interconnecting said lines, a single motor controller associated with the links and adapted to operate in synchronism with each one of the automatic switches in a succession of links, in a forward direction 75 only, series circuit connections adapted to be completed between the automatic switch and the said motor in building up the desired connection, means controlled by said switch for periodically making and breaking said circuit whereby said motor is stepped in synchronism, means controlled by said motor to interrupt said circuit and determine the extent of travel in the synchronous operation, and means determining the forward 80 movement of the motor prior to interruption of the operating circuit.

8. In a telephone exchange system, a plurality of lines, links having selector switches for interconnecting them, a step by step motor outside of the link and means for connecting the same therewith for synchronous movement with the selector switch in a forward direction, means determining the extent of the forward movement of the motor, and means thereupon becoming active to return the motor to a defined normal position.

9. In a telephone exchange system, subscribers' lines, a link circuit having a selector switch for interconnecting the same, a step by step motor outside of the link and means for connecting the same therewith for synchronous movement with said selector switch in a forward direction, means for predetermining the synchronous movement 100 of said automatic switch and motor, and control devices thereupon becoming active to return the motor to a defined normal position in a forward direction.

10. In a telephone exchange system, subscribers' lines, a connective link containing automatic two-motion switches for interconnecting the same, a motor without the link and means for connecting the motor with the link for operation in synchronism with the primary movement of an automatic switch, means controlled by the motor limiting the primary movement of the switch, motor control means active to return the motor to normal at the termination of the synchronous operation as aforesaid, and means to send a shifting impulse to said automatic switch during the return to normal movement of the motor.

11. In a telephone exchange system, a plu- 130

- rality of lines, a connective link containing automatic two-motion switches to interconnect the same, a motor without the link and means for connecting the same with the 5 same for synchronous movement with one of said automatic switches in the forward direction only, means determining the extent of synchronous operation of said switch with said motor, motor control means continuing the movement in the forward direction thereafter, and circuits and connections controlled in said continued movement of the motor to transmit a shifting impulse to said automatic switch, whereby its secondary 10 movement is started.
12. In a telephone exchange system, a plurality of lines, a connective link containing automatic switches for interconnecting the same, a motor without the link and means for connecting the same with the same for synchronous operation with one of said automatic switches, means determining the extent of operation of said switch in synchronism with said motor, motor control 15 means continuing the movement of said motor in the same direction thereafter, and means to send a shifting impulse to said automatic switch operated by said motor in its continued forward movement.
13. In a telephone exchange system, subscribers' lines, connective links containing automatic two-motion switches for interconnecting the same, a motor without the links and means to connect the motor singly with the links for synchronous operation with an 20 automatic switch of the connected link, means determining the extent of operation of said switches in synchronism with said motor, means to send a shifting impulse following the synchronous operation of said 25 motor and connected switch, and time operated motor control devices controlling said motor to prevent further synchronous operation of said motor for a predetermined time whereby the secondary motion of said selector switch may be completed without interference.
14. In a telephone exchange system, subscribers' lines, a plurality of links having automatic switches for interconnecting the same, a motor without the links adapted to operate in synchronism with the automatic switches of the links and having a predetermined cycle of motion, circuits and connections between said links and switches and said motor whereby said motor is operated in synchronism with a switch of any single link for a predetermined portion of its cycle of motion, and time element control means thereupon becoming operative to complete the cycle of said motor.
15. In a telephone exchange system, subscribers' lines, a plurality of connective links having automatic switches, a step by step motor without the links having a predetermined cycle of motion, circuits and connections whereby said motor may be connected with an automatic switch of any single one of said links and operated in synchronism with said automatic switch, means coöperating with said motor to determine the extent of synchronous operation of said switch with said motor, time element control means thereupon becoming operative to complete the cycle of said motor after the aforesaid synchronous operation, and means to send a shifting impulse to said automatic switch a predetermined time before the completion of the cycle of operation of the motor.
- In testimony whereof I affix my signature in presence of two witnesses.
- EDWARD E. CLEMENT.
